ABSTRACT OF THE DISCLOSURE

A card for mailing currency, the card having a special pocket for holding a bill or check as well as the usual coin receiving openings.

Background of the invention

This invention relates generally to coin holding cards, and has particular reference to a novel card of this type which is additionally provided with a separate and easily usable bill receiving pocket.

For many years coin cards, or coin holding cards, which are principally used for sending small coins through the mail, have been constructed with coin receiving openings only. Cards with such a construction are disclosed in U.S. Pat. No. 673,299, issued Apr. 30, 1901 to J. N. Spies and No. 789,076, issued May 2, 1905 to J. E. Trahan et al., both owned by the assignee of the present invention. To the best of applicant's knowledge, none of the prior art cards has provided any type of bill receiving pocket or opening except in a makeshift manner. Thus, it has been suggested that a bill can be folded and inserted in one of the coin openings; however, the bill does not fit properly, and if folded small enough to fit within the area of the opening, it becomes far too thick.

Summary of the invention

The invention contemplates a currency holding card assembly that is comprised of a relatively stiff card having coin receiving openings and a backing member that is secured to one side of the card. The backing member is of sheet material such as paper and forms with the card a convenient pocket for receiving a bill or check, the bill pocket being separate from and independent of the coin receiving openings. Access to the bill receiving pocket is gained through an opening at the edge of the card, and the pocket is provided with a window so that it can be determined by visual inspection whether or not a bill has been placed in the pocket. The backing member includes a flap portion that extends outwardly from the card and is adapted to be folded into overlying engagement with the other side thereof, in so doing, the flap covers the access opening for the bill receiving pocket.

For insertion into the bill receiving pocket, a bill or averaged size check need only be folded twice so that when folded it is still very thin and does not measurably increase the overall thickness of the card. In addition, the bill pocket opening is easily accessible and the pocket itself is dimensioned so that a bill can be readily inserted in and removed from it.

Brief description of the drawings

FIG. 1 is a top plan view of a currency holding card embodying the invention, with the cover flap shown in open position;

FIG. 2 is a vertical section through the card taken substantially on line 2—2 of FIG. 1;

FIG. 3 is a vertical section through the card taken substantially on line 3—3 of FIG. 1; and

FIG. 4 is a right end elevation of the card of FIG. 1 showing the cover flap folded into closed position.

2

Description of the preferred embodiment

With reference now to the drawings, 10 generally designates a card which may be made of any suitable material but is preferably formed of a relatively stiff paperboard. As shown, the card is rectangular in shape and is provided with a plurality of coin receiving openings 12 which extend all the way through the card. Coacting with each opening is an integral retaining strip 14 which is adapted to releasably hold a coin in the opening, the strips being sprung out from the face of the card for this purpose as described in Pat. No. 673,299, supra. The thickness of card 10 is preferably at least as great as that of the thickest coin the card is adapted to receive.

15 A backing member 16 is secured as by adhesive means to the under side of card 10, the member being of sheet material such as paper. The backing member forms a bottom closure for the coin receiving openings 12 and also coacts with the card to form a bill receiving pocket 18. Thus, the backing member is not secured to the card in the area enclosed by the dash line 20, FIGS. 1 and 2, but is secured along that line and elsewhere to define a pocket of substantially rectangular shape between the card and member.

20 The opening for the bill receiving pocket 18 is at the edge 22 of the card where the backing member 16 is not secured to it. The pocket is dimensioned to receive with ample clearance a bill that has been folded twice as indicated at 24 in FIG. 1. It will, of course, be apparent that pocket 18 can be used also for a folded check, and the term "bill" as used herein is intended to include paper money, checks and the like. The card is formed with an aperture 26 which serves as a window for the pocket 18 whereby it can readily be determined by visual inspection whether or not a bill has been inserted in the pocket.

25 The backing member 16 includes a flap 28 which extends outwardly from one edge of the card 10 as shown in FIG. 1. This flap is adapted to be folded into overlying engagement with the upper side of the card and is dimensioned so as to be coextensive therewith as indicated by FIG. 4. Since the flap extends from the edge of the card where the access opening for the bill receiving pocket is located, the fold of the flap operates as a closure for the pocket when the flap is in its FIG. 4 position.

30 From the foregoing description, it will be apparent that the invention disclosed herein provides a currency holding card that is more versatile and efficient than the coin cards of the prior art while at the same time having a simple, inexpensive construction. As will be understood by those familiar with the art, the invention may be embodied in other specific forms without departing from the spirit or essential characteristics thereof. The embodiment disclosed is, therefore, to be considered in all respects as illustrative rather than restrictive.

What is claimed is:

35 1. A currency holding card comprising a relatively stiff card member formed with at least one coin receiving opening and having means for retaining a coin in the opening, and a backing member secured to the card member and forming therewith a bill receiving pocket adjacent one edge of the card member, said pocket being separated from said coin receiving opening.

2. A currency holding card as defined in claim 1 wherein the card is formed with an aperture in communication with the bill receiving pocket for indicating whether or not a bill has been inserted in the pocket.

40 3. A currency holding card as defined in claim 1 wherein the backing member is a sheet member secured to one side of the card, said sheet member including a flap portion that extends outwardly from the card and is adapted to be folded into overlying engagement with the other side thereof.

4. An article of the character described comprising a relatively stiff card member formed with a plurality of coin receiving openings spaced from one another and from the peripheral edges of the card, said card member having retaining means for releasably holding coins in the openings, and a sheet member backing secured to one side of said card member and forming therewith a substantially rectangular bill receiving pocket, said pocket being formed so as to have an access opening adjacent one edge of the card member and being spaced from said coin receiving openings.

5. An article as defined in claim 4 wherein said bill receiving pocket is formed with a window for enabling it to be determined by visual inspection whether or not a bill has been inserted in the pocket.

6. An article as defined in claim 4 wherein the thickness of the card member is at least as great as that of the thickest coin the card is adapted to receive.

7. An article as defined in claim 4 wherein the sheet member backing includes a flap portion that extends outwardly from one edge of the card member and is adapted to be folded into overlying engagement with the other side thereof.

8. An article as defined in claim 7 wherein the access opening for said bill receiving pocket is located adjacent the edge of the card member from which said flap portion extends whereby the opening is covered by the flap when the latter is folded into overlying engagement with said card other side.
